2 Sheets-Sheet 2

UNITED STATES PATENT OFFICE.

DANIEL SHAW MONROE, OF PORTLAND, OREGON.

OILING DEVICE FOR ROAD ROLLERS.

Application filed January 18, 1922. Serial No. 530,212.

To all whom it may concern:

Be it known that I, DANIEL S. MONROE, a citizen of the United States, residing at Portland, in the county of Multnomah and 5 State of Oregon, have invented a new and useful Improvement in Oiling Devices for Road Rollers, of which the following is a specification.

This invention relates to road rollers, and 10 is more particularly directed to an oiling device for oiling the surfaces of the pressure rollers of a road roller.

An object of this invention is the provision of a new and improved oiling means 15 for spraying oil on the front and rear pressure rollers by means of an ejector operated by the steam from the engine which drives the road roller, and which is controlled by the engineer from his position on the road 20 roller, whereby it is unnecessary for him to subject himself to possibility of danger by being compelled to work among the moving parts of the road roller in order to adjust the flow of oil.

25 The invention will be best understood from a consideration of the following detailed description taken in connection with the accompanying drawing forming part of this specification, with the understanding, 30 however, that the invention is not confined to any strict conformity with the showing in the drawing, but may be changed and modified so long as such changes and modifications mark no material departure from 35 the salient features of the invention as expressed in the appended claims.

In the drawing:-

Fig. 1 is a side elevation of a road roller disclosing my oil spraying device in operative relation to the pressure rollers.

Fig. 2 is a plan view of the same with parts removed, disclosing the spraying device in operative relation to the pressure rollers.

45 Fig. 3 is a longitudinal section of the ejector.

Fig. 4 is a detail view in section of one of the nozzles of the spraying devices.

Generally speaking, the oil spraying device 50 comprises a source of oil, an ejector connected with the source of oil, conduits connecting the ejector with the steam engine, discharge pipes connecting the ejector with spraying devices associated with the front and rear pressure rollers, and valves

for controlling the flow of steam and oil through their respective conduits.

Referring more particularly to the drawing, 1 designates a steam engine with its boiler carried by the front pressure rollers 60 2, and the rear pressure rollers 3 and 4. A controlling means 5 for guiding the front pressure rollers 2 is adapted to direct the movement of the road roller. These elements are old in the art and form no part 65 of the present invention.

Supported in baskets 6 are oil containers or reservoirs 7 and 8, located upon opposite sides of the engine and boiler 1. Plugs 9 close an opening in the top of the containers 7 and 8 and provide means by which oil may be supplied to the containers. The container or reservoir 7 is provided with a connection 10 for a conduit 11. A check valve 12 is mounted in the conduit 11 and 70 permits oil to flow from the container through said pipe, but will prevent the oil or other fluid from re-entering the reservoir 7. A stop cock 13 is likewise mounted in the pipe 11 and is provided with a handle 14 for operating the valve. An operating rod 15 extending rearwardly of the road roller is mounted near its outer end in a bracket 16 and provided with handles 17 adapted to be gripped by the engineer, 75 whereby the stop cock 13 may be operated from the seat of the engineer.

A vertical pipe 18 is connected at its lower end to the pipe 11 and at its upper 80 end to an ejector 19.

The ejector 19 as shown in Fig. 3 comprises a steam nozzle 20 seated in one end of the casing 21 of the ejector, and is held in place by means of a nipple 22, engaged by the annular flange of a union 23, having 85 screw-threaded engagement with the externally threaded outer end of the casing 21. In the other end of the casing 21 is screw threaded an ejector tube 24 provided with external threads engaging the internal 90 threads in the forward end of the casing 21. The ejector tube 24 is of a larger diameter than the steam nozzle 20, but of smaller 95 diameter than the pipe 18.

The nipple 22 is externally threaded and 100 screwed into the internally threaded end of a steam conduit 25, which extends rearwardly of the road roller, and is connected to the steam chest of the engine at 26, Fig. 2. A globe valve 27 is located in the steam 110

pipe 25 for controlling the flow of steam from the engine to the ejector 19. A handle 28 is provided for operating the valve 27.

Connected to the forward end of the casting 21 of the ejector is a short pipe 29 (Fig. 3) which is connected by an elbow 30 to a vertical discharge pipe 31. The vertical discharge pipe is provided with a check valve 32 (Fig. 1).

10 This valve 32 is only useful when it is desired to supply the sprayer with water. The pipe 31 is connected by a T-coupling 34 to the forward and rearward discharge pipes 35 and 36, respectively. The discharge pipe 35 extends downwardly and is connected to a horizontal discharge pipe 39 (Fig. 2). A support 38 secured to the boiler 1 and to the T-coupling 34 maintains the discharge pipes 35 and 36 in position. The discharge pipe 39 is provided with a check valve 40 which permits fluid to pass forwardly and out of the pipe 39 to the T-connection 41, but prevents fluid from returning to said pipe. A flexible tubing 42 provides a connection between the T-connection 41 and the front spraying device 43, which is adapted to spray oil onto the front pressure rollers 2.

The rearwardly-extending discharge pipe 36 is provided with a valve 44 operated by a handle 45 to cut off communication between the ejector 19 and the rear spraying device 46, associated with the rear pressure roller 3.

35 The handle 45 may be connected by means of an operating rod similar to the rod 15 and directed rearwardly to a point near the seat of the engineer, whereby the valve 44 may be controlled remotely from its position on the pipe 46. This obviates the necessity of the engineer working among the moving parts of the road roller when he desires to regulate the oiling device.

40 As shown in Fig. 2, the parts just described comprising the ejector, the oil reservoir and the several discharge conduits leading to the front and rear of the road roller, are duplicated on the other side of the road roller.

An ejector 47 similar to the ejector 19, is connected to the steam engine by means of a conduit 48 running rearwardly of the road roller and parallel to the steam conduit 25, the flow of steam being controlled by a valve 49 operated by a handle 50.

55 A stop cock 51 which controls the flow of the oil from the reservoir 8 to the ejector 47, is provided with a lever 52 connected to an operating rod 53 running rearwardly. The rod 53 has a handle 17 similarly located near the seat of the engineer as is the handle 17 for the rod 15. The ejector 47 is connected by a rearwardly-extending discharge pipe 54 to a spraying device 55 associated with the rear pressure roller 4. A forwardly and downwardly extending dis-

charge pipe 56 is connected to a horizontally and inwardly extending discharge pipe 57, which is connected to the T-connection 41, to which the horizontal discharge pipe 39 is connected. The discharge pipes 39 and 57 70 cooperate to feed the front spraying device 43 with oil from their respective containers 7 and 8 by the action of the ejectors 19 and 47. A check valve 58 is located in the discharge pipe 57 to permit oil to flow to the 75 flexible tubing 42, but prevent oil from the discharge pipe 39 from flowing backwardly into the pipe 57.

A check valve 59 similar to the check valve 12 is employed in the discharge conduit leading directly from the oil reservoir 8 to prevent fluid from entering the reservoir when steam under an excessive amount of pressure tends to act rearwardly in the discharge conduits located between the reservoir 8 and the ejector 47.

80 A manually controlled valve 60 similar to valve 44 is located in the discharge conduit 54 and operated by a lever 61 for cutting off communication between the rear spraying device 55 associated with the rear pressure roller 4 and the ejector 47.

85 Each of the small perforations located in the spraying devices 43, 46 and 55 is provided with a nipple 62, upon which is 90 mounted a short length of rubber tubing 63 of substantially the same diameter as the nipple 62 but longer than said nipple. The portion of the tubing which extends beyond the nipple provides a means for directing 95 the oil from the several spraying devices onto the respective pressure rollers. Furthermore, it may be stated that by this construction oil is forced directly from the spraying devices onto the wheels of the pressure rollers, and the oil is thus protected 100 from strong winds which would tend to blow the oil away from the rollers (Fig. 4).

105 In operation, the tanks 7 and 8 are filled with oil for lubricating the rims of the pressure rollers 2, 3 and 4 to prevent the hot dressing of the roadbed from adhering to 110 said rims. As long as the pressure rollers are traveling over the surface of the freshly treated roadbed, it is necessary that said 115 rollers be constantly sprayed with oil. Since the spraying devices 43, 46 and 55 are in constant operation, a considerable amount of oil must be supplied to them, and therefore a tank having a capacity of at least six 120 gallons each is desirable. The check valves 12 and 59 permit oil to flow through the containers 7 and 8, respectively, but prevent any liquid from returning to said reservoirs 125 or containers.

130 Rods 15 and 53, respectively, operate the respective stop cocks 13 and 51, whereby the amount of oil flowing from the reservoirs 7 and 8 is regulated, and since these rods extend to the rear of the power plant and near

the engineer's seat, they may be controlled from that position without it being necessary for the engineer to leave the road roller.

When the stop cock 13 is open, oil will flow through the conduits 11 and 18 to the ejector 19, and will be forcibly carried through the discharge conduits 35 and 36, respectively, to the front spraying device 43 and to the rear spraying device 46, thus spraying the forward pressure rollers 2 and the rear pressure roller 3, when the valve 27 has been opened to admit steam from the boiler 1 to the pipe 25.

When the stop cock 51 is opened, oil will be admitted to the ejector 47, and then forced through the discharge pipes 54 and 56 by means of steam from the pipe 48 when the valve 49 is opened to admit steam from the boiler 1 to the pipe 48. Oil is thus forced along the discharge pipes 54 and 56, respectively, to the rear spraying device 55 associated with the pressure roller 4 and to the forward spraying device 43 associated with the front pressure rollers 2.

It will be seen that oil is fed to the front spraying device 43 by both ejectors 19 and 47, while the respective ejectors 19 and 47 supply independently the rear spraying devices 46 and 55.

It will be unnecessary always to supply one of the two pressure rollers 3 and 4 with oil, since it frequently happens that only one of these pressure rollers is in operative position for rolling the newly treated roadbed. Therefore, valve 44 may be closed to cut out communication between the ejector 19 and the spraying device 46, when the operating handle 45 of the valve 44 is manipulated. Valve 60 may be operated to cut off communication between the ejector 47 and the spraying device 55 associated with the rear pressure roller 4.

It will be seen that by closing the valves 44 and 60, either one of the spraying devices 46 or 55 may be cut off from the supply of oil, but at no time will the front spraying device 43 be cut off from the ejectors 19 and 47, since the front pressure rollers 2 will always be employed in rolling the roadbed when the road roller is in operation.

The check valves 40 and 58 are supplied to the discharge conduits 39 and 57, respectively, to prevent oil discharged by either ejector 19 or 47, from passing from one side of the road roller to the other, and entering either one of the discharge pipes, when either valve 44 or 60 cuts off communication between the respective spraying devices 46 and 55, as for example, when the rear spraying device 46 is cut out of communication with the ejector 19, greater pressure will be exerted upon the oil delivered to the discharge conduit 39 and to the front spraying device 43. In this case,

there will be a tendency to force oil not only into the spraying device 43, but also into the discharge conduit 57 and towards the ejector 47, and along the discharge conduit 54 to the rear spraying device 55, as 70 associated with the rear pressure roller 4. In this case there would be a tendency to supply more oil to the rear spraying device 55 than is necessary, but the check valve 58 which permits oil to flow from the discharge conduit 57 to the front spraying device 43, will prevent oil from the discharge conduit 39 from entering the discharge conduit 57.

The same conditions will arise for supplying a greater quantity of oil to the sprayer 46 when the rear spraying device 55 is cut off from communication with the ejector 47, and when the rear spraying device 46 is in communication with the injector 19. The check valve 40 will prevent oil in the discharge conduit 57 from entering the discharge conduit 39 and the discharge conduit 36 to the other rear spraying device 46 associated with the pressure roller 3.

The flexible pipe 42 is used to connect the T-connection 41 with the front spraying device 43, and as such permits the front pressure rollers 2 to be turned on their axes 95 when the pressure rollers are operated to guide the road rollers by the controlling means 5.

While I have shown the oiling device applied to a three wheel road roller, nevertheless it may be equally well applied to the smaller or tandem rollers which are used in the city. In such case, but one oil reservoir and one ejector will be employed, in co-operation with a single spraying device for each pressure roller similar to the front spraying device 43 shown in Fig. 2. This construction has not been disclosed since it is thought unnecessary to illustrate the numerous forms to which the spraying device may be applied. No new problem is involved in applying the oil spraying system to the different forms of road rollers, since the principle employed for spraying the pressure rollers and the manner of controlling the spray will be the same.

What is claimed is:

1. In a road roller provided with a steam generator, an oiling device for the pressure roller, comprising an oil reservoir, an ejector, pipes connecting the ejector with the steam generator and the oil reservoir, a discharge conduit connected to the ejector, spraying means connected to the discharge conduit and leading to the surface of a roller, and means for controlling the flow of steam to the ejector and thereby controlling the discharge of the oil from the spraying means.

2. In a road roller provided with a steam generator, an oiling device for the pressure

roller comprising an oil reservoir, an ejector, separate pipes connecting the ejector with the steam generator and with the oil reservoir, a discharge conduit connected to the 5 ejector, spraying means adjacent to the pressure roller and connected to the discharge conduit, a valve for controlling the flow of steam to the ejector and thereby controlling the discharge of the oil from the 10 spraying means, a separate valve for controlling the flow of oil from the reservoir to the ejector, and a check valve between the last mentioned valve and the oil reservoir to prevent steam from entering the oil 15 reservoir.

3. In a road roller provided with a steam generator and front and rear pressure rollers, an oiling device for the pressure rollers comprising an oil reservoir, an 20 ejector, a pipe directly connecting the ejector with the steam generator and a pipe directly connecting the ejector with the oil reservoir, discharge conduits directly connected to the 25 ejector and extending forwardly and rearwardly, spraying means adjacent the pressure rollers and connected to the discharge conduits, means controlling the flow of steam to the ejector, and means for cutting off communication between the ejector and 30 the spraying device associated with the rear pressure roller.

4. In a road roller provided with a steam generator, front pressure rollers and rear pressure rollers, an oiling device for the 35 pressure rollers comprising a plurality of ejectors, each ejector having communication with the steam generator and with a source of oil, discharge conduits connected to the ejectors, spraying devices associated with each pressure roller and having communication with the discharge conduits and ejectors cooperating with each other to supply oil simultaneously to the spraying device associated with the front pressure roller, means for cutting off communication between one ejector and the spraying device associated with one of the rear pressure rollers, and means to prevent steam from either ejector from forcing oil into the spraying 45 means associated with the other rear pressure roller.

5. In a road roller provided with a steam generator and front pressure rollers and rear pressure rollers, an oiling device for 50 all the pressure rollers comprising a plurality of oil reservoirs, a plurality of ejectors each having separate communication with an oil reservoir and with the steam generator, means to control the flow of steam to each ejector, oil spraying means associated with each pressure roller, a discharge conduit connected with each ejector and having communication with a common discharge pipe connected to the spraying means associated 55 with the front rollers, each of the discharge

conduits being connected with a spraying means associated with each rear roller, and means for cutting off communication between said discharge conduits and either one of the spraying devices associated with a rear 70 pressure roller, whereby the ejectors simultaneously supply oil to the front rollers and each ejector supplies oil to one rear roller.

6. In a road roller provided with a steam 75 generator and a front roller having steering means, an oiling device for said roller comprising an oil reservoir, an ejector, a pipe for directly connecting the ejector with the steam generator, means for controlling the flow of steam through said pipe, a pipe directly connecting the ejector with the oil reservoir, means for controlling the flow of oil through the last-mentioned pipe, a discharge conduit directly connected to the 80 ejector, transversely arranged spraying means for the front roller, a transversely disposed discharge pipe connected to the discharge conduit, and a flexible tube connecting the discharge pipe with the spraying 85 means intermediately of the length thereof, whereby the front roller may be turned at any angle without affecting the pipes.

7. In a road roller provided with a steam generator, a front roller having steering means, and a rear roller or rollers, an oiling device for all of said rollers comprising a pair of oil reservoirs and a pair of ejectors, one of each at each side, a pipe for directly connecting each ejector to the steam generator, means for controlling the flow of steam through said pipes, a pipe directly connecting each ejector with an oil reservoir, means for controlling the flow of oil through the last-mentioned pipes, a separate discharge conduit directly connected to each 95 ejector, a transversely-arranged spraying means for the front roller, a transversely arranged discharge pipe connected at its 100 ends to the two discharge conduits, a flexible 105 tubular connection between the discharge pipe and the said spraying means, whereby the front roller may be steered at any angle 110 without affecting the said pipes, a pair of check valves in said discharge pipe, one at 115 each side of the said tubular connection, a separate spraying means for said rear roller or rollers, a pipe or pipes leading rearwardly from said discharge conduit to said separate 120 spraying means, and means for controlling communication through said pipe or pipes, whereby the front roller is continuously 125 sprayed with oil and the spraying means for the rear roller or rollers may be cut off at will.

In testimony that I claim the foregoing as my own, I have hereto affixed my signature.

DANIEL SHAW MONROE.
